UNITED STATES PATENT OFFICE

2,046,502

PROCESS FOR THE PYROLYTIC DECOMPOSITION OF HYDROCARBONS

Maurice B. Cooke, New York, N. Y.

Application March 12, 1932, Serial No. 598,504

1 Claim. (CL 196—67)

My invention relates to a process for the pyrolytic decomposition of hydrocarbon oils to form gasoline-like hydrocarbons suitable for using as a motor fuel having high antiknock qualities. 5 The process is usually known as a "cracking" process and relates more particularly to the cracking of hydrocarbons in the vapor phase by hot gases of combustion.

When fuel is burned with no excess of air, the 10 temperature of combustion is between 3,000° and 4,000° F. These temperatures are too high for efficient cracking and accordingly they must be tempered or brought down to about 1,500° F. in order to give an efficient cracking process.

16 In an application of William O. Keeling, Serial No. 586,573, now U. S. Patent 1,991,750, a method of tempering the combustion gases by means of a cooler, inert gas is disclosed.

This application relates to an improvement in 20 my co-pending application, Serial No. 598,502, filed March 12, 1932, now Patent No. 2,016,798, issued October 8, 1935 to Maurice B. Cooke.

When a great volume of gas is introduced into the fractionating tower, many disadvantages result. 25 The equipment must be made a larger size. The volume of gas to be compressed for absorption purposes is so increased that the process becomes expensive. The use of a cool, inert gas to temper the combustion gases represents a direct loss of 30 heat besides increasing the volume of the gases to be handled.

One object of my invention is to avoid the disadvantages above pointed out, with special reference to reducing the volume of the gas to be 35 handled in the fractionating equipment.

It will be noted that the instant invention differs from my above mentioned co-pending application in that I use steam to give an additional heat carrier and to temper the hot products of 40 combustion, so that the separation of the water in the pre-fractionation condensing stage will enable the use of a smaller main fractionating tower.

Another object of my invention is to partially 45 temper the hot products of combustion by steam.

A further object of my invention is to provide a process in which fractionating equipment of small dimensions may be used due to the fact that no considerable amount of flue gas or fixed gas 50 pass through the fractionating zone.

Another object of my invention is to provide a process in which the hot gases of combustion are tempered by means of heat exchange.

A further object of my invention is to employ 55 the gas heat for topping the charging stock, va-

porizing the charging stock for conversion into the vapor phase and supplying heat for other purposes such as distilling or the generation or high superheating of steam.

Still another object of my invention is to provide a vapor phase cracking process in which hot gases of combustion are used to supply the cracking heat which is flexible of control and efficient in operation. 5

Still another object of my invention is to check 10 the reaction to prevent over-cracking by means of shock chilling the products of reaction.

Other objects of my invention will appear from the following description:

The figure shows a diagrammatic view of one 15 embodiment of the process of my invention.

In general, my invention consists in burning fuel and air with surface combustion in a furnace to supply hot gases of combustion substantially devoid of free oxygen. I charge crude oil from 20 storage through suitable heat exchangers into an accumulator tank. Oil is pumped from the accumulator tank through a coil situated in my furnace where the heat necessary to convert a substantial portion of the charging stock into 25 vapors is supplied. The temperature of the hot gases of combustion will be lowered and lose part of their heat in heating the oil in the coil and thus be tempered by indirect heat exchange. The heated charging stock is passed into a flash 30 evaporator whence the vapors are withdrawn and passed to the cracking zone. In the cracking zone the vaporized hydrocarbons encounter the hot gases of combustion which have been tempered to about 1,500° F. The hot gases of combustion 35 admixing with the vapors bring the mixture to about 1,050° F. at which temperature cracking takes place rapidly. The increase in volume is accommodated for by a progressively increasing cross sectional area. After leaving the 40 cracking zone, the products of the reaction are shock chilled by means of an oil spray. The products, after being chilled, pass into a tar separator. The tar laden quenching oil is drawn through a cooler and pumped to storage and may be used 45 for fuel oil. The vapors and gases are passed through a sectional entrainment condenser through suitable heat exchangers and into a separator, whence the uncondensed gases are withdrawn overhead and allowed to pass into 50 the gas main. It will be noted that this is the novel step in which the excess and uncondensed gases are withdrawn from the system in order to prevent their being passed through the fractionating tower. The water is withdrawn from 55

the bottom of the separator. The condensate is then pumped from the separator through suitable heat exchangers through a second coil in my furnace where the condensate will be re-vaporized. The re-vaporized products are passed into the fractionating tower.

The condensate formed in the entrainment condenser collects in suitable pockets and may be passed either into the separator or into a fractionating tower depending upon their nature and character.

The reflux condensate from the fractionating tower is withdrawn and pumped through a cooler in order to reduce the temperature thereof to render it suitable as a quenching medium. After passing through the cooler, it is passed through the sprays in order to be used in the chilling zone. A portion of the reflux condensate from the fractionating tower may be diverted into the accumulator for recycling. The vapors withdrawn from the fractionating tower are cooled and passed into a separator from which the water is withdrawn. The condensate is withdrawn as gasoline and passed to storage.

More particularly, referring now to the drawings, gas from the gas main 1 is taken through branch line 2, through compressor 3, into gas supply tank 4, from which it passes through line 5, valve 6, into the mixing chamber 7 of the surface combustion burner. Compressed air entering through line 8 passes through valve 9 into the mixing chamber 7, where the mixture thus formed will burn with surface combustion on the granules of refractory material 10 to form hot gases of combustion in the combustion chamber 11. Hydrocarbon oil to be processed enters through line 12, passes through valve 13 and is pumped by pump 14 through line 15, through heat exchanger 16, through line 17, to the accumulator 18. The oil thus preheated leaves the accumulator 18 through line 19 and is pumped by pump 20 through valve 21, through line 22, into the heating coil 23. The incoming charge passing through heating coil 23 will temper the hot products of combustion entering the furnace 24. In so doing, the charge will be itself heated to a vaporizing temperature. The oil leaves the heating coil 23 through line 25 and passes into the flash evaporator 26 in which the heated oil is flashed into vapors. The unvaporized portion is withdrawn from the bottom of the flash evaporator through the line 27, through valve 28, through heat exchanger 29, through cooler 30, and is pumped by pump 31 to storage through line 32 for use as a fuel oil. The vaporized oil leaves the flash evaporator through line 33 and valve 33' and passes into the mixing zone 34 in which the hydrocarbon vapors are commingled with the hot products of combustion coming from the furnace 24. After being admixed the reaction will take place in the cracking zone 35 in which the hydrocarbon vapors are pyrolytically decomposed to form hydrocarbons having a lower molecular weight and suitable for use as a motor fuel. A chamber of progressively increasing volume is provided to permit the expansion to take place without building up back pressure. After the reaction has progressed for a sufficient interval of time, inasmuch as the reaction at the temperature of 1,050° F. will take place very rapidly, I provide oil sprays 36, 37 and 38 for quenching the hot products to check the reaction in order to prevent overcracking. The hot gases of combustion, it will be remembered, are generated at a temperature between 3,000° F. and 4,000° F.

After tempering the hot products of combustion will have a temperature of about 1,500° F. When the oil vapors from the flash evaporator are admixed with the hot gas of combustion at a temperature of 1,500° F., the resultant mixture will have a temperature of about 1,050° F., at which the cracking takes place.

After the reaction has been checked by quenching, the products pass into the separator 39. The heavy, tarry residue which forms in the separator 39 is withdrawn from the bottom thereof through line 40 and is passed through heat exchanger 29, cooler 30, to fuel oil storage, together with the vaporized oil from the flash evaporator coming through line 27.

The vapors and gases which will be largely vapors containing the products of reaction, gases and steam, are withdrawn from the separator through line 41 and passed into the sectional entrainment condenser. The temperature of the vapors entering the sectional entrainment condenser will be in the neighborhood of 750° F.

I pump clean water through valve controlled line 42 by pump 43, through line 44, through heat exchanger 45, into line 46, whence the incoming water will pass through the tubes 47 of the sectional entrainment condenser 48. It is to be noted that the incoming water will pass in counterflow relation to cool the vapors entering the sectional entrainment condenser through line 41. The water will be converted into steam which leaves the tubes 47 and passes into line 49 into the steam supply tank 50 which is suitably lagged to prevent heat radiation, as is all other equipment in which high temperatures exist.

Steam from the steam supply tank passes through line 51 through valve 52 and is allowed to enter the zone above the point of complete combustion of the surface combustion burner, at 53. It will be noted that the steam admixing with the hot combustion gases from the surface combustion burner at 53 will partially reduce the temperature of the hot combustion gases to bring them nearer the temperature at which the reaction takes place. The steam thus supplied will furnish an additional heat carrier medium, and has the advantage of being condensable enabling the reduction of the quantity of fixed gas which must pass through the fractionating tower. This will enable me to use a smaller main fractionating tower than has heretofore been used in the processes of my copending applications Serial No. 585,488, filed January 8, 1932, and Serial No. 598,502, filed March 12, 1932, now U. S. Patent 2,016,798.

The condensate formed in the sectional entrainment condenser will collect in pockets 54', 55' and 56', whence it may be passed in whole or in part into the separator or fractionating tower through lines 57' and 58', respectively, by the agency of valves 59', 60', 61' and 62'. The products are then withdrawn from the sectional entrainment condenser through line 63' and pass through heat exchanger 45, heat exchanger 46' and cooler 47' into the separator 48'. The incoming fresh water to be converted into steam is the cooling medium for heat exchanger 45. The cooler 47' is cooled by circulating water coming through line 49' from cooling water main 50'. The uncondensed gases are withdrawn from separator 48' through line 98 and pass into gas main 1.

The steam which has been introduced to temper the hot combustion gases, and such steam as results from the combustion of the fuel in the

burner, is condensed in the bottom of the separator 48' from which it is drawn off through line 51'. The condensed products are pumped through line 52' by pump 53', through heat exchanger 46', and into line 54, which terminates in a manifold. A portion of the condensate may be diverted through valve controlled line 55 into line 22 for recycling. The condensate normally passes through valve controlled line 56 through heat exchanger 57, into line 58, line 59, through heat exchanger 29, into line 60, whence it passes to a second coil 61 situated in the furnace 24. A portion of condensate passing through heat exchanger 57 may be diverted through line 62 and passed into line 22 for recycling. The heat exchanger 57 may be by-passed, if desired, by valve controlled line 63. The condensate in passing through coil 61, will temper in part the products of combustion, and will itself be revaporized.

20 The vapors leave the coil 61 through line 64 and pass into the fractionating tower 65.

Steam may be drawn from the supply tank 50 through line 66 and injected into the fractionating tower through valve 67, for stripping the heavy fractions of the lighter vapors. The reflux condensate in the fractionating tower is withdrawn through line 68 and passed through line 69, through heat exchanger 57, and pumped by pump 70 through cooler 71, through line 72 and valve controlled branch lines 73, 74 and 75 for delivery to quenching sprays 36, 37 and 38 respectively. A portion of the reflux condensate of the fractionating tower may be diverted through valve controlled line 76 and passed into the accumulator 18 for recycling.

The vapors from the fractionating tower pass through line 82, through heat exchanger 16, through cooler 83, through line 84 into separator 85. A portion of the steam will be condensed in cooler 83 and will form water in the bottom of the separator 85. This water is withdrawn through line 86. The gasoline-like hydrocarbons are withdrawn through line 87 and passed to storage.

It will be appreciated that my process has many advantages. I temper the hot products of combustion by means of heat exchange and use the heat obtained by tempering to perform useful steps in my process. The thermal efficiency of my process will be exceedingly high. The flexibility of control is manifest. The temperature of the combustion gases, the temperature of the quenching oil and hence the temperature of reaction may be controlled within close limits. I am enabled, by my process, to crack hydrocarbon oil in the vapor phase and obtain a gasoline-like hydrocarbon suitable for use as a motor fuel and having an exceedingly high antiknock value. I may use a portion of the gas formed in my process for other purposes where gaseous fuel may be needed. It will be noted that the cracking reaction takes place in the pure vapor phase, it being impossible for any hydrocarbon oil which is not in the vapor form to be present. This insures the absence of the danger of the formation of coke or

carbon deposits within my cracking zone. It will be understood, of course, that suitable lagging is provided throughout the piping and the piece of apparatus used in my process to prevent the loss of heat by radiation. By withdrawing a large quantity of the gas from the system before fractionating the products of combustion, and tempering by steam I am enabled to avoid large fractionating equipment and to dispense with the necessity of treating a disproportionate amount of gas in my gasoline absorption treatment.

It will be understood that certain features and sub-combinations and operations are of utility and may be employed without reference to other features and sub-combinations. This is contemplated by and is within the scope of my claim. It is further obvious that various changes may be made in details within the scope of my claim without departing from the spirit of my invention. It is, therefore, to be understood that my invention is not to be limited to the specific details shown and described.

By this method of cracking hydrocarbons in the vapor phase, in which the hydrocarbons are combined with the combustion gases, the latter being maintained at selected, controlled, temperatures of reaction, a motor fuel having a high octane number and high antiknock value is obtained. The process eliminates parasitic cracking which accompanies conventional cracking methods, in which the hydrocarbons are converted in tubular containers and heated by external circulation of the combustion gases thereabout. The intimate mixture of the combustion gases with the hydrocarbon vapor produces a distribution of heat impossible with the conventional tubular cracking processes.

Having thus described my invention, what I claim is:

A process for converting hydrocarbon oils into lower boiling hydrocarbons including the steps of generating hot gases of combustion, heating a hydrocarbon oil to vaporizing temperatures by passing the same in an elongated confined stream in heat exchange relation with the hot gases of combustion, controlling the temperature of the hot gases by mixing steam therewith, separating the heated oil into vapors and unvaporized oil and admixing the vapors with hot gases of combustion which have been tempered by heating the oil and by mixing steam therewith, allowing a time interval of reaction and then arresting the reaction by spraying cool oil in contact with the reacting mixture, condensing the products of reaction, separating the condensate from the uncondensed gases, revaporizing the condensate by passing the condensate in an elongated confined stream in heat exchange with the hot gases to supply the heat of vaporization and to further temper the hot gases of combustion and fractionating the vapors to recover lower boiling hydrocarbons.

MAURICE B. COOKE.
